Primary Examiner — John R Yeh

(74) *Attorney, Agent, or Firm* — Ricky Lam

(57) **CLAIM**

The ornamental design for a carpet rake as shown and described.

DESCRIPTION

FIG. 1 is a front, top, and left perspective view of a carpet rake showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear, bottom, and right perspective view thereof;

FIG. 9 is an enlarged view of the portion indicated with the number **9** in FIG. 1;

FIG. 10 is an enlarged view of the portion indicated with the number **10** in FIG. 1;

FIG. 11 is an enlarged view of the portion indicated with the number **11** in FIG. 2;

FIG. 12 is an enlarged view of the portion indicated with the number **12** in FIG. 4;

FIG. 13 is an enlarged view of the portion indicated with the number **13** in FIG. 6;

FIG. 14 is an enlarged view of the portion indicated with the number **14** in FIG. 7; and,

FIG. 15 is an enlarged view of the portion indicated with the number **15** in FIG. 8.

The broken lines shown in the drawings represent portions of the carpet rake that form no part of the claimed design. The dot-dash broken lines encircling an enlargement portion of the design forms no part of the claimed design.

1 Claim, 15 Drawing Sheets
